UNITED STATES PATENT OFFICE.

CHARLES K. VOLCKENING, OF NEW YORK, N. Y.

BOTTLE-WASHER BRUSH.

1,160,551.

Specification of Letters Patent. Patented Nov. 16, 1915.

Application filed May 7, 1915. Serial No. 26,455.

To all whom it may concern:

Be it known that I, CHARLES K. VOLCKENING, a citizen of the United States, residing in the city of New York, borough of Brooklyn, in the county of Kings and State of New York, have invented new and useful Improvements in Bottle-Washer Brushes, of which the following is a specification.

My invention relates to bottle washer-brushes of a kind suitable for use in connection with streams of water and revolvably driven by power for the purpose of cleaning bottles internally.

My invention can be made in various forms, but for the sake of conciseness I will describe only two such forms; it being understood, however, that I do not wish to be limited by so doing, as the scope of my invention is commensurate with my claims.

Reference is made to the accompanying drawing forming a part of this specification, and in which like letters indicate like parts in all of the views.

Figure 1 is a perspective of one form of my brush. Fig. 2 is a section on the line 2—2 of Fig. 1, looking in the direction of the arrows. Fig. 3 is a perspective of the ferrule for supporting the brush. Fig. 4 is a perspective of another form of my brush. Fig. 5 is a section on the line 5—5 of Fig. 4, looking in the direction indicated by the arrows. Fig. 6 is a section on the line 6—6 of Fig. 1, looking in the direction of the arrows.

The body member 6 is provided with a frusto-conical portion 6^a and with a pair of fins 7, these fins extending in opposite directions. A central stem 8 extends from the body member 6, and a pair of operating arms 9, carried by the central stem 8, diverge slightly from each other, and with the stem 8 constitute a member of Y-form. A pair of ribs 10 extend along opposite sides of the stem 8 and continue along the operating arms 9. The ribs 10 thus strengthen the stem 8 and the arms 9. The brush is provided with a water hole 11, extending axially through the body member 6 and central stem 8, terminating in a slot 11^a, which serves as a discharge orifice. The free ends of the operating arms 9 are provided with relatively narrow portions 13, which are flexible and therefore adapted to bend abruptly or gradually as required by their environment from time to time.

The arms 9 are each provided with a rib 12 and with a groove 12^a, these parts being so mated that when the arms 9 are brought together the rib 12 of each arm fits into the groove 12^a of the other arm. Thus when the arms are pressed together in order to facilitate the entrance of the brush into the bottle through the neck thereof, the parts are closed together and the ribs 12 are not exposed. Yet when the brush is in the bottle and the arms 9 are pressed against the bottom thereof, the ribs 12 serve as operating members for scrubbing the bottom of the bottle.

Extending from the body member 6 and diverging from the latter and from each other are a pair of leaf stems 14, each having the proximate general form of a semi-cone. Each leaf stem 14 carries a number of leaves 15, 16, 17, 18, of different lengths, integral with it and spaced slightly apart so that they can be bent separately and somewhat independently of each other. The leaf 15 has a rounded corner 15^a for engaging curved portions of the inner surface of the bottle. The leaf 18 has a general triangular form, and the leaves 15, 16, 17 are of different lengths. The stem 14 terminates in a sharp point 19, which coincides with one corner of the triangular leaf 18. Each leaf stem 14 has a groove 20 of substantially semi-conical form, so disposed as to receive the adjacent rib 10 when the arms 14 are pressed against the stem 9, thus partially enclosing the central stem 8. The leaves 15, 16, 17, 18 are provided with ribs 15^b, 16^a, 17^a, 18^a, each leaf carrying a pair of these ribs, disposed upon its opposite faces and beveled, as shown at 15^b, in Fig. 2. The purpose of the ribs 15^b, 16^a, 17^a and 18^a is to serve as auxiliary scrubbing surfaces, so that when the leaves 15, 16, 17 and 18 are bent or flexed, by engagement of their outer ends against the inner surface of the bottle, the ribs are also forced into engagement with said inner surface. Each leaf therefore presents, to the inner surface of the bottle, a plurality of scrubbing surfaces differing in character.

For mounting the brush I use the ferrule shown in Fig. 3. A body member 22 is provided with an extending portion 23 of reduced diameter, this portion being provided with annular corrugations or threads 24, and with a smooth end portion 25. A hole 26 extends axially through the ferrule 22.

from end to end. Another hole 27 extends through the wall of the body member 22, and merges into the hole 26. These two holes 26 and 27, because of the purpose for which used, I designate as water holes.

In order to fit the brush upon the ferrule, the reduced portion 23 is forced into the hole 6^a of the brush, the body portion 6 stretching slightly, so that a water-tight fit is made.

10 In the form of brush shown in Fig. 4 the body member appears at 28, and is provided with a frusto-conical portion 29 and with a pair of oppositely disposed ribs 30. Integral with the body member 28 and diverging therefrom are a pair of leaf stems 31, each having a flat face 32 and also having in cross section a substantially semi-cylindrical form, as indicated in Fig. 5. The outer or rounded surface of each leaf stem 32 is provided with a series of leaves 33, 35, 36, 37, the leaf 33 having a rounded corner 34 and being of a form similar to that of the leaves 15 above described, the leaves 35, 36, 37 being of similar form to the leaves 16, 17, 18. The flat faces 32, or inner surfaces of the leaf stems 31, are each provided with a number of leaves 38, 40, 41, 42 and 43, spaced slightly apart and adapted to bend or yield separately if necessary. The leaves 38 are provided with edges 39 which abut closely together. The several leaves 38, 40, 41, 42 and 43 vary in length as measured laterally from the leaf stem 31. Each leaf stem ends in a sharp point 44, and to this point converge the outer edges of the adjacent groups of leaves. That is to say, the outer or free ends of the leaves 33, 35, 36 and 37 are in line with the point 44, and this is also true of the oppositely-disposed or free ends of the leaves 38, 40, 41, 42 and 43. The leaves 33, 35, 36, 37 carry ribs 46, 47, 48, 49 similar to the ribs 15^b, 16^a, 17^a, 18^a above described. The leaves 38, 40, 41, 42 and 43 carry ribs 50, 51, 52 and 53 and 54. 15 The cross section of the ribs 46 and 51 is shown in Fig. 5 and from this illustration the form of the other ribs, similar in kind may be understood and their action comprehended.

50 Either form of brush may be used for bottles of different kinds but the form shown in Figs. 1 and 2 is specially adapted for bottles with flat bottoms while the form appearing in Fig. 4 is suitable for bottles with bottoms projecting inwardly—for instance champagne bottles.

The operation of my device may be readily understood from the foregoing description.

60 The brush being mounted upon the ferrule as above described and the ferrule being mounted in the usual manner upon a tubular shaft through which water flows, the brush is used for washing the internal surfaces of bottles. The leaves 15, 16, 17, 18 at their outer ends engage the cylindrical portions

of the bottle, the leaf 15 also engaging the portions adjacent the bottle neck. The ribs carried by the leaves also engage the internal surface of the bottle. The operating arms 9 are pressed against the bottom of the bottle, and because of their resilience and flexibility they bend or yield in such manner as to fit neatly against said bottom, even if the same be flat. The ribs 12, by their scrubbing action, increase the efficiency of the arms 9.

70 The leaves 40, 41, 42 and 43 shown in Fig. 4, also engage the bottom of the bottle, and yielding or bending independently of each other they conform to some extent to the adjacent surface of the bottom, which as above indicated may be raised or extend inwardly some distance. At the same time the ribs 50, 51, 52, 53 and 54 are pressed against the bottom and thus they assist in cleaning the same. Each leaf thus has two surfaces in engagement with the bottom of the bottle.

75 I claim:—

1. A bottle washer brush comprising a body-member of resilient material, a stem extending from said body member and integral therewith, said stem having the general proximate form of a semi-cone, a plurality of leaves carried by said stem and being of different lengths for the purpose of 80 engaging predetermined inner surfaces of the bottle to be cleaned, and means carried by said stem and independent of said leaves for engaging other inner surfaces of said bottle.

90 2. A bottle washer brush comprising a body-member of resilient material, a stem made of resilient material and integral with said body member, said stem having the general proximate form of a semi-cone, a plurality of leaves carried by said stem and having different lengths, one of said leaves having a rounded operating surface, all of 95 said leaves having outer edges disposed in alignment with each other and with the apex 100 of said semi-cone.

105 3. In a bottle washer brush the combination of a body member made of resilient material and provided with a water hole disposed axially thereof said body member being further provided with a pair of leaf stems integral with it and diverging from each other, each leaf stem having a plurality of leaves integral therewith and made of resilient material, said leaves being of different lengths and normally extending to a 110 line disposed parallel to said water hole.

115 4. In a bottle washer brush the combination of a body member of resilient material provided with a centrally-disposed water hole, a pair of leaf stems of resilient material integral with said body member and located upon opposite sides of said water hole, leaves carried by said leaf stem, and a 120 plurality of ribs carried by said body mem- 125

ber and disposed adjacent said stems in order to brace the same.

5. A bottle washer brush comprising a body member of resilient material, a centrally-disposed stem extending from said body member and integral therewith, said body member and stem having a water hole extending therethrough, operating members carried by said stem for the purpose of engaging a predetermined inner surface of a bottle, and other operating members carried by said body member for engaging another predetermined inner surface of said bottle.

6. A bottle washer brush comprising a body member, a pair of leaf stems integral therewith and extending therefrom, each leaf stem having the general proximate form of a solid-semi-cone, a plurality of leaves carried by said stem and disposed upon the convex surface thereof, and a plurality of other leaves carried by said stem and disposed upon the flat side thereof.

7. A bottle washer brush comprising a body member, a pair of leaf stems integral therewith and extending therefrom, each leaf stem having a plurality of leaves disconnected from each other and free to bend independently of each other, said leaves being arranged in groups, the leaves of one group being located upon the opposite side

of the stem from the leaves of the other group.

8. A bottle washer brush comprising a body member, a pair of leaf stems carried thereby and diverging from each other, each leaf stem having the general proximate form of a hollow semi-cone, leaves carried by each leaf stem, a central stem carried by said body member and located intermediate said leaf stems, said central stem having ribs around which said leaf stems can fit when pressed thereagainst, and operating members carried by said central stem for engaging a predetermined part of the inner surface of a bottle.

9. A bottle washer brush comprising a body member, a stem extending therefrom, and a plurality of arms of resilient material carried by said stem, each arm having a groove and a rib, said arms being so disposed that the stem of one arm can enter the groove of another when said arms are pressed together.

In witness whereof, I have hereunto signed my name.

CHARLES K. VOLCKENING.
